UNITED STATES PATENT OFFICE.

LE ROY W. FAIRCHILD, OF NEW YORK, N. Y.

DESIGN FOR PENCIL-CASES.

Specification forming part of Design No. **11,416**, dated September 16, 1879; application filed August 7, 1879.
[Term of patent 7 years.]

To all whom it may concern:

Be it known that I, LE ROY W. FAIRCHILD, of the city, county, and State of New York, have produced a new and original Design for a Pencil-Case, or other small implement case intended to be worn upon a watch-chain, of which the following is a full, clear, and exact description, reference being had to the accompanying engraved illustration, making a part of this specification.

The invention consists in making said implement-case in the form of a field-bat, such as is used in playing the game known as "lacrosse or lawn tennis."

A represents the complete design, which

will be improved by the employment of different colors in its manufacture. *b* is the pencil barrel or case proper, and forms the handle of the bat. *c* is the blade, consisting of a bowed rim and netted center or interior. *d* is a ball affixed to the interior netting. *e* is a ring.

What I claim as my invention is—

The design consisting of the cylindrical handle *b*, ring *e*, netted blade *c*, and ball *d*, substantially as shown and described.

LE ROY W. FAIRCHILD.
